US00D826054S

(12) **United States Design Patent** (10) **Patent No.:** **US D826,054 S**
Trombetta (45) **Date of Patent:** **** Aug. 21, 2018**

(54) **CAPSULE**(71) Applicant: **2266170 Ontario Inc.**, Mississauga (CA)(72) Inventor: **Liberatore A. Trombetta**, Ancaster (CA)(73) Assignee: **2266170 Ontario Inc.** (CA)(***) Term: **15 Years**(21) Appl. No.: **29/587,969**(22) Filed: **Dec. 16, 2016****Related U.S. Application Data**

(62) Division of application No. 29/523,741, filed on Apr. 13, 2015, now Pat. No. Des. 778,157.

(51) **LOC (11) Cl.** ..... **09-01**(52) **U.S. Cl.**USPC ..... **D9/503**(58) **Field of Classification Search**

USPC D3/201; D7/396.1, 550.1, 553.1, 553.2, D7/553.3, 554.4, 601, 602, 629, 400, D7/509-511, 523, 590, 603, 612, 615, D7/630; D9/414-416, 418-421, D9/423-426, 428-436, 455-457, 499, D9/443, 438, 440, 447, 500, 503-505, D9/516, 518, 549, 558, 715, 716, 719

CLAIM

The ornamental design for a capsule, as shown and described.

DESCRIPTION

FIG. 1 is a front perspective view of a capsule showing my new design;

FIG. 2 is a rear perspective view thereof;
 FIG. 3 is a front view thereof;
 FIG. 4 is a rear view thereof;
 FIG. 5 is a right side view thereof;
 FIG. 6 is a left side thereof;
 FIG. 7 is a top view thereof;
 FIG. 8 is a bottom view thereof;
 FIG. 9 is another top view thereof, showing the word "TEXT" in broken lines;
 FIG. 10 is a front perspective view of a second embodiment thereof;
 FIG. 11 is a rear perspective view thereof;
 FIG. 12 is a front view thereof;
 FIG. 13 is a rear view thereof;
 FIG. 14 is a right side view thereof;
 FIG. 15 is a left side view thereof;
 FIG. 16 is a top view thereof;
 FIG. 17 is a bottom view thereof;
 FIG. 18 is another top view thereof, showing the word "TEXT" in broken lines;
 FIG. 19 is a front perspective view of a third embodiment thereof;
 FIG. 20 is a rear perspective view thereof;
 FIG. 21 is a front view thereof;
 FIG. 22 is a rear view thereof;
 FIG. 23 is a right side view thereof;
 FIG. 24 is a left side thereof;
 FIG. 25 is a top view thereof;
 FIG. 26 is a bottom view thereof; and,
 FIG. 27 is another top view thereof, showing the word "TEXT" in broken lines.
 The dashed broken lines illustrate structure or features that form no part of the claimed design.
